GUSTAF ERIKSON, OF SÖDERTELJE, SWEDEN, ASSIGNOR TO VAGNFABRIKS AKTIEBOLAGET I SÖDERTELJE, OF SÖDERTELJE, SWEDEN.

FOUR-CYCLE EXPLOSIVE-VAPOR ENGINE.

SPECIFICATION forming part of Letters Patent No. 706,733, dated August 12, 1902.

Application filed October 9, 1901. Serial No. 78,029. (No model.)

To all whom it may concern:

Be it known that I, GUSTAF ERIKSON, a subject of the King of Sweden and Norway, residing at Södertelje, in the Kingdom of Sweden, have invented certain Improvements in Internal-Combustion Engines, of which the following is a specification.

This invention relates to four-cycle internal-combustion engines or explosive-vapor engines of the type provided with automatic admission-valves; and the object of the invention is to provide means for governing the power and rotary speed of an engine of this class or type. One defect found in engines of this type now in use is their inability to vary speed and torque within wide limits. For this reason it has not been found feasible in many instances to substitute internal-combustion engines for steam-engines or electric motors. An instance of this kind is an engine for operating a machine-tool where a variable speed with a constant torque is required. Another instance is the employment of an engine for propelling a vehicle where it is necessary to introduce complicated gearing between the motor and the vehicle-wheels in order to control the speed of the vehicle.

The present engine, in which my invention is embodied, is capable of variation in velocity within wide limits as readily as a steam-engine or electric motor, and, furthermore, it will adjust itself automatically to variations in load, so that when the load increases the torque is also increased in proportion to the increase in the load, the rotary velocity being, however, proportionately reduced.

In the accompanying drawings, which serve to illustrate an embodiment of the invention, Figure 1 is a sectional side elevation of the engine, and Fig. 2 is a plan of the same. Fig. 3 is an enlarged sectional view of the dash-pot device.

A is the cylinder of the engine, B the piston therein, and J the connecting-rod which couples the piston to the crank K on the main shaft Q. This shaft has bearings in the casting U.

P is the vapor-inlet to the ignition-chamber C, the admission being controlled by a valve D.

E is the exhaust-valve, I is its stem, and H its spring. This valve is opened at each

fourth stroke of the engine by an opening-rod T, actuated by a cam S on a counter-shaft R, driven by suitable gearing from the engine-shaft Q.

55

All of the above features are known in this class of engines and are employed herein to illustrate the application to such an engine of the present invention, which will now be described with especial reference to Figs. 1 60 and 3.

On the stem I of the exhaust-valve E is secured a piston F, which plays in a fixed cylinder or pot G, forming a dash-pot device. The rod I plays snugly through an aperture 65 in the closed end of the cylinder G, and there is an inlet or port L in the cylinder to admit air to the latter back of the piston through an aperture O, Fig. 3, and to allow the incarcerated air to escape. The port L is controlled by a screw-valve M. In the side of the cylinder G is an air-inlet port N, which is opened to the atmosphere when the piston is drawn out to a predetermined extent. The object of the dash-pot is to retard the closing 70 of the exhaust-valve by its spring through the incarceration of air in the cylinder behind the piston, the time of escape of the air at the port L being regulable by the valve M.

The time required for the closing of the exhaust-valve depends on the strength of the closing-spring H of the valve and the resistance to the spring offered by the gradually-escaping incarcerated air behind the piston of the dash - pot. This resistance can 75 obviously be varied by means of the valve M, thus making the closing period of the valve of longer or shorter duration at will within limits. The means employed for opening the exhaust-valve are such as to permit the lat- 80

ter to close under normal conditions or without a dash-pot when the engine is on the dead-center. The closing period of the exhaust-valve is intimately connected with the cycle of operations within the motor, since 85 the automatic admission-valve cannot open during the suction-stroke until the exhaust-valve is closed and a vacuum has been subsequently formed. Before the closing of the exhaust - valve the waste gases are drawn 90

back into the cylinder in quantity determined by the shorter or longer closing period 95

of the exhaust-valve. The quantity of explosive mixture subsequently drawn in is thus made dependent on the quantity of waste gases previously drawn back—that is, on the 5 relation of the closing moment of the exhaust-valve to the beginning of the suction-stroke.

By using a device for controlling the closing period of the exhaust-valve it is possible, first, to vary the power of the engine while 10 retaining a constant velocity; second, to vary the velocity of the engine under a constant load, and, third, to obtain automatic governing control of the power and velocity of the engine according to the variations in load.

15 Case 1. When the engine is running at a constant velocity and the resistance of the dash-pot is varied, the moment of closing the exhaust-valve will be varied, a greater or less quantity of waste gases will be drawn back, 20 a smaller or greater quantity of explosive mixture drawn in, and as a result the violence of the explosions and the power of the engine will be varied.

Case 2. With a constant load if the resistance offered by the dash-pot be decreased the 25 exhaust-valve will close earlier on the suction-stroke, a smaller quantity of waste gases will be drawn back, a larger quantity of explosive mixture will be drawn in, the violence of the 30 explosions will increase, and the velocity of the engine will be correspondingly increased. In consequence of the increased speed of the engine, however, the closing of the exhaust-valve on the suction-stroke will soon be restored to the original moment in relation to the 35 suction-stroke and a condition of continuance will be maintained. When the resistance offered by the dash-pot is increased, a diminished velocity will result.

40 Case 3. If the load increases while the resistance offered by dash-pot is constant or permanently adjusted, the velocity of the engine will decrease and the moment of closing of the exhaust-valve will occur earlier on the 45 suction-stroke. As a result a smaller quantity of waste gases will be drawn back, a larger quantity of explosive mixture will be drawn in, and the explosions will increase in violence. This will continue until the closing of the 50 exhaust-valve on the suction-stroke shall occur at such a time as to barely admit of a quantity of explosive mixture being drawn in sufficient for the increased velocity, a condition of continuance at a decreased velocity now beginning. The reverse action will take place 55 when the load is decreased.

The passages L and O of the dash-pot are made large, so that when they are fully open the dash-pot will make no appreciable resistance and the exhaust-valve can close when the engine is at or near the dead-center.

60 I have shown a simple dash-pot device for effecting the object sought—namely, to more or less weaken the explosive mixture, so as to

modify the force of the explosion; but I do 65 not limit myself to this particular means for effecting the above object, as other equivalent means may be employed as well. The dash-pot device may be located and operated in any manner, so long as it accomplishes the 70 object stated. As the admission-valve with this governing means always permits of completely filling the cylinder, the compression always remains constant. As a result the ignition is always insured, even when the charges 75 are weak, this not always being the case with the mode of governing by means of throttling. In governing by means of throttling the compression falls with the throttling. Consequently the ignition becomes uncertain 80 when the charges are weak, and the effect is lowered.

Having now described my invention, what I claim as new, and desire to obtain by Letters Patent, is—

1. A four-cycle internal-combustion engine having a suction admission-valve for the explosive mixture, a valve communicating with the explosion-chamber and closing outward, automatic means for opening said valve at 90 regular intervals, a spring for closing said valve, and dash-pot device for retarding the closing of the last-named valve after the beginning of the suction-stroke, substantially as set forth.

2. A four-cycle internal-combustion engine having as an automatic means for controlling the sucking in of the explosive mixture, an exhaust-valve communicating with the explosion-chamber, means operated by the engine for opening said valve at regular intervals, a spring for closing said valve, and means for retarding the closing of said valve by its spring, said means comprising a fixed cylinder having an inlet for air and a valve-controlled outlet for the same, and a piston in said cylinder and fixed on the stem of the last-named valve, substantially as set forth.

3. A four-cycle internal-combustion engine having a suction admission-valve for the explosive mixture, an exhaust-valve, automatic means for opening said exhaust-valve at all times to the same extent, a spring which closes said valve, and means for retarding the exhaust-valve, said means comprising a 110 fixed cylinder or pot G, having a lateral air-inlet N and a valve-controlled outlet O, a screw-valve M controlling said outlet, and a piston F, in said cylinder or pot and connected with the stem of the exhaust-valve.

In witness whereof I have hereunto signed my name in the presence of two subscribing witnesses.

GUSTAF ERIKSON.
